Primary Examiner—Stella Reid*Attorney, Agent, or Firm*—Richard C. Litman[57] **CLAIM**

The ornamental design for a bottle support, as shown and described.

DESCRIPTION

FIG. 1 is a perspective view of a bottle support showing my new design;

FIG. 2 is a front elevational view thereof;

FIG. 3 is a rear elevational view thereof;

FIG. 4 is a left side view thereof, the right side being a mirror image;

FIG. 5 is a top plan view thereof; and,

FIG. 6 is a perspective view of an alternate embodiment thereof, with all other sides being identical to that shown in FIGS. 3-5.

The bottom of the design is plain and unornamented.

FIG. 2

FIG. 3

FIG. 4

FIG. 5
